UNITED STATES PATENT OFFICE.

JAMES MAURICE NEWALL, OF SEAORTH, ENGLAND.

FASTENING FOR DOORS, WINDOWS, &c.

No. 798,694.

Specification of Letters Patent.

Patented Sept. 5, 1905.

Application filed December 22, 1904. Serial No. 237,968.

To all whom it may concern:

Be it known that I, JAMES MAURICE NEWALL, engineer, M. I. M. E., a subject of the King of Great Britain and Ireland, and a resident of 5 11 Beaconsfield road, Seaforth, in the county of Lancaster, England, have invented certain new and useful Improvements in Fastenings for Doors, Windows, or the Like, of which the following is a specification.

10 This invention has reference more particularly to a fastening for doors, and has for its object to provide a fastening by means of which the door may be opened to some extent by the occupier of a room—say for the purpose of ventilation—but without permitting the door to be opened farther from the outside.

15 I will describe my invention with the aid of the accompanying drawings, in which—

20 Figure 1 is a sectional elevation of the appliance as fitted in connection with a door, the door being closed. Fig. 2 is a front view. Fig. 3 is a view showing the door ajar and secured in this position.

25 Referring now to the drawings, *a* represents the door, and *b* the jamb or door-frame. *c* is a bracket secured to the jamb *b*, to which an arm *f* is pivoted, as at *c'*.

30 *e* designates a bolt or projection which forms an extension of the loose sleeve *d*, carried by arm *f*. As shown, the bolt *e* is adapted to slide in and out of the guide-plate *g*, fitted to door *a*. This guide-plate is slotted and is closed at one end, *h* and *i* being the closed

35 and open ends, respectively. The bolt-head is $\perp$ or ball shaped in order to prevent its lifting out of engagement with guide-plate *g*.

40 A stop *k* is fixed in the end of arm *f* by being driven or secured therein, and through this stop passes a sliding rod *l*. A stop *m* is secured to the inner end of this rod, and between the stops *k* and *m* is coiled a spring *j*. On the outer end of the rod *l* outside the arm *f* is secured a head *k'*. By this arrangement

45 the sliding bolt *e* is prevented from accidentally moving entirely out of engagement with the guide *g*, as the part *k'* prevents it; but of course slight pressure on the part of the person using the fastening will entirely free the bolt from the guide *g*.

50 *n* is a pinching-screw by means of which the bolt may be secured in any desired position on the arm *f*, so that the amount of opening of the door *a* may be regulated as required.

55 *o* represents rubber sheathings which may

be employed to prevent rattling of the appliance.

In use when the door is tightly closed the bolt on the pivoted arm *f* is placed in engagement with the guide *g*, as shown in Fig. 1 of 60 the drawings, and by securing the bolt by the pinching-screw *n* the door may be locked in this position.

In some cases I may provide a hook *p* on sleeve *d*, which is adapted to engage in a hole 65 *q* in *g*, by which the door may be hooked open and unhooked from the outside.

To open the door for ventilation, bolt *e* is released by unscrewing *n*, when the door may be opened to any desired extent (the amount 70 of opening being regulated by the length of arm *f*) and secured again by the pinching-screw *n*. To free the door entirely from the fastening, the door is first closed, when bolt *e* may be slid out of guide *g* and the arm *f* 75 turned about its pivot out of the path of the door.

In some cases the pivoted arm may be attached to the door and the guide attached to the jamb or door-frame. 80

It will be seen that it is only possible to remove the fastening when the door is entirely closed.

While my invention has been described as 85 being more particularly applicable as a fastening for doors, it may also be employed in connection with windows as "French" windows or as a fastening in connection with other hinged or pivoted articles.

Having now described my invention, what I 90 claim as new, and desire to secure by Letters Patent, is—

1. A fastening for doors, windows, or the like, comprising an arm *f* pivoted as at *C'*; a sliding bolt *e* carried by sleeve *d*; a guide-plate 95 *g* closed at one end and open at the other end, with which said bolt *e* is adapted to engage; a pinching-screw *n*; a spring *j* disposed around a rod *l* between a fixed stop *k* and a stop *m* connected with said rod *l*; and a movable 100 head *k'* also connected to said rod *l*, for the purpose described.

2. A fastener for doors, windows, or the like, comprising an arm *f* pivoted as at *o'*; a sliding bolt *e* carried by sleeve *d*; a guide-plate 105 *g* closed at one end and open at the other end with which said bolt *e* is adapted to engage; a pinching-screw *n*; a spring *j* disposed around a rod *l* between a fixed stop *k* and a stop *m* connected with said rod *l*; a movable 110

head k' also connected to said rod l and rubber sheathings as o , for the purpose specified.

3. A fastening for doors, windows, or the like, comprising an arm f pivoted as at C' ; a sliding bolt e carried by sleeve d ; a guide-plate g closed at one end and open at the other end, and with which said bolt e is adapted to engage; a pinching-screw n ; and a part k'

controlled by a spring j for the purpose described.

In testimony whereof I have signed my name in the presence of two subscribing witnesses.

JAMES MAURICE NEWALL.
